UNITED STATES PATENT OFFICE.

MICHAEL LIPTAK, OF ST. PAUL, MINNESOTA, ASSIGNOR TO LIPTAK FIRE BRICK ARCH CO., OF MINNEAPOLIS, MINNESOTA, A CORPORATION OF MINNESOTA.

FURNACE ARCH.

Application filed May 31, 1919. Serial No. 301,024.

To all whom it may concern:

Be it known that I, MICHAEL LIPTAK, a citizen of the United States, residing at St. Paul, in the county of Ramsey and State of Minnesota, have invented certain new and useful Improvements in Furnace Arches; and I do hereby declare the following to be a full, clear, and exact description of the invention, such as will enable others skilled in the art to which it appertains to make and use the same.

My invention relates to fire arches for boilers or steam generating plants, and has for its object to improve the same in the several particulars hereinafter disclosed. Generally stated, the invention consists of the novel devices and combinations of devices hereinafter described and defined in the claims.

20 In the accompanying drawings which illustrate the invention, like characters indicate like parts throughout the several views.

Referring to the drawings:—

25 Fig. 1 is a perspective view with some parts removed and some parts broken away, illustrating the improved arch and showing the rear portion thereof;

30 Fig. 2 is a fragmentary view in side elevation illustrating the manner in which the laterally spaced beam and beam tips are hung from the main beams of the arch;

35 Fig. 2^a is an elevation looking at the parts shown in Fig. 2 in a direction from the right toward the left, in respect to said Fig. 2;

Fig. 3 is a section taken through a portion of the arch, some parts being removed;

Fig. 4 is a perspective view of one of the main arch blocks;

40 Fig. 4^a is a view corresponding to Fig. 4, but showing the form of block used to replace the former in making repairs;

Fig. 5 is a perspective view showing one section of one of the supplemental blocks;

45 Fig. 6 is a perspective view of one of the main corner blocks;

Fig. 7 is a perspective view of one of the supplemental corner blocks; and

Fig. 8 is a perspective view of one of the corner filler blocks.

50 The furnace arch will occupy the usual position between masonry walls 9. Main arch supporting beams 10, the rear one of which is shown in the drawings, preferably in the form of I-beams, extend transversely of the arch from one wall 9 to the other. A multi-

plicity of laterally spaced forwardly and rearwardly extended beams 11 are located below and hung from the main beams 10 in a manner presently to be noted. These beams 11 are also preferable I-beams, but their lower flanges are preferably turned slightly downward so that they converge in an upward direction. Only one of the main beams 10 is shown in the drawings, but the second main beam, not shown, would be located above the outer end portions of the beams 11. At their inner ends, the beams 11 are provided with upstanding T-shaped necks 12. For each beam 11 there is a short beam herein called a detachable beam tip 11^a. These beam tips 11^a have the same cross sectional form as the beams 11, and at their rear ends, are provided with upstanding T-shaped webs 12^a that correspond in cross section to the webs 12. The T-shaped webs 12 and 12^a of the beams 11 and beam tips 11^a ride upon and are interlocked with T-shaped channels formed in the underside of the bracket-like beam hangers 13, which beam hangers are channeled on their upper faces for interlocking sliding engagement with the lower flanges of the overlying main beams. By the beam hangers 13, therefore, the beams 11 and the beam tips 11^a are detachably and independently hung from the main beams, inasmuch as either of the webs 12 or 12^a may be slid from position without disturbing the other.

90 The main arch forming blocks 14 shown in Figs. 1, 3 and 4 have heavy rectangular lower portions which, when the blocks are assembled, form the undersurface of fire exposed surface of the main portion of the arch, but they are provided with reduced upper neck portions 14^a and with outstanding upper flanges 14^b. The flanges 14^b are adapted to overlap and rest upon the upper flanges of the beams 11 and to thereby support the main blocks with large clearance between the upper neck portions of the said blocks and said laterally spaced beams 11. To protect the lower portions of the beams 11 from the fire, even if one or more of the main blocks should be burned away or broken, I provide supplemental blocks adapted to nearly fill the said space and to be independently hung from the lower flanges of the said beams 11. These supplemental blocks are each made up of two sections 15; each section having an oblique 100

channel forming hook-like portion adapting the said block sections to be hung in the opposite upturned lower edge flanges of the said beams 11.

5. The main block shown in Fig. 4^a and at the left in Fig. 3, is adapted to replace the main block 14 that has been broken and dropped from position, or has been burned away. This replacing block 16 has a base 10 or lower portion like the block 14 and has a reduced neck portion 16^a, but instead of forming the flanges 14^b projecting transversely of the block, is provided with longitudinally projecting flanges 16^b that are 15 adapted to be passed upward through the space between adjacent supplemental blocks. This replacing block can therefore be pushed upward to position in the arch from beneath, and when it is in position, it is adapted to 20 be hung from the upper flanges of the beams 11 by short metal bars 17 applied to the upper flanges of said beams and under the flanges 16^b of the said blocks 16.
- This form of replacing blocks makes it 25 unnecessary to slide a number of the main blocks from position in order to replace a block at any portion of the arch.

- The main corner block 18, shown in detail in Fig. 6, but also shown in Fig. 1, has a 30 neck portion 18^a and upper edge flanges 18^b corresponding to the parts 14^a and 14^b of the blocks 14, and which adapt the said main corner blocks to be hung on the upper flanges of the beam extensions 11^a, with the 35 inner ends of said blocks projecting beyond the inner ends of the said beam tips. The lower portions of these main corner blocks 18 are shown as narrower than the lower portions of the main blocks 14 and the spacing between the same is, in the construction 40 illustrated, arranged to be closed up by corner filler blocks 19. These filler blocks 19 have upper flanges 19^a that rest upon outstanding ledges 18^c of the blocks 18.
45. The supplemental blocks 20, in their main cross section, are like the supplemental blocks 15, that is, they are made in sections and the sections have channels adapting them to be hung on the lower flanges of the 50 beam tips 11^a, but the said channels terminate short of the inner ends of the inner exposed ends of the block sections 20, so that the solid ends of the said block sections protect the ends of the beam tips, as best shown 55 in Fig. 1.

A fire arch constructed as described, is not only highly efficient and has a very long life, but may be very quickly and easily erected in the first place, and may be rapidly 60 and cheaply repaired.

What I claim is:

1. A fire arch comprising laterally spaced beams, main blocks hung from said beams and forming the under fire exposed surface 65 of the arch, said main blocks having chan-

neled sides, and supplemental blocks located in the channeled side of said main blocks and hung from and protecting the lower portions of said beams independent of said main blocks.

2. A fire arch comprising laterally spaced beams, main blocks hung from said beams and forming the under fire exposed surface of the arch, said main blocks having channeled sides, and supplemental blocks located 70 in the channeled side of said main blocks and hung from and protecting the lower portions of said beams, the said supplemental blocks being divided with sections thereof hung on opposite sides of the respective 75 beams.

3. A fire arch comprising laterally spaced beams having upper and lower flanges, main blocks, with channeled sides, and upper end flanges, said flanges being seated on the upper flanges of said beams and the lower portions of the said main blocks forming the under fire exposed surface of the arch, and divided supplemental blocks located in the 85 channel sides of said main blocks and independently hung on the lower flanges of the 90 respective beams.

4. A fire arch comprising laterally spaced beams, main blocks hung from said beams and provided with reduced upper portions, the lower portions of said blocks forming the under fire exposed surfaces of the arch, and supplemental blocks located between the reduced upper portions of said main blocks and independently hung from and protecting 95 the lower portions of said beams.

5. A fire arch comprising laterally spaced beams, main blocks having transversely reduced neck portions that are formed with flanges, means for hanging the said blocks 105 from said beams, and supplemental blocks located between the neck portions of said main blocks and independently hung on and protecting said beams.

6. A fire arch comprising laterally spaced beams, main blocks having transversely reduced neck portions that are formed with flanges, means for hanging the said blocks from said beams, and supplemental blocks located between the neck portions of said 110 main blocks and independently hung on and protecting said beams, the said supplemental blocks being divided and the sections thereof being hung on opposite sides of the 115 respective beams.

7. A fire arch comprising laterally spaced beams, main blocks having transversely reduced neck portions that are formed with flanges, means for hanging the said blocks from said beams, supplemental blocks located between the neck portions of said main blocks and independently hung on and protecting said beams, main corner blocks 120 hung on said beams and projecting inward thereof, supplemental corner blocks located 125 130

between the upper portions of said main blocks and independently hung on said beams and projecting inward thereof, and filler blocks located between and hung from 5 said main corner blocks and completing the inner end structure of the arch.

8. In a fire arch, the combination with laterally spaced flanged I-beams with upwardly diverging lower flanges, of main blocks hung 10 from the upper flanges of said beams, divided supplemental blocks located between the upper portions of said main blocks, the sections of said supplemental blocks being formed with channels adapting them to be 15 independently hung on the lower flanges of said beams.

9. A fire arch comprising laterally spaced

beams having detachable beam tips, main blocks hung from said beams and forming the under fire exposed surface of the arch, 20 said main blocks having channeled sides, and supplemental blocks located in the channeled side of said main blocks and hung from and protecting the lower portions of said beams, arch forming blocks hung from said laterally spaced beams, and corner blocks removably hung from said beam tips.

In testimony whereof I affix my signature in presence of two witnesses.

MICHAEL LIPTAK.
